UNITED STATES PATENT OFFICE

155,109

DESIGN FOR A FRUIT PACK

Ernest L. Shepard, Fairfield, Maine

Application June 26, 1947, Serial No. 139,930

Term of patent 14 years

(Cl. D58—13)

To all whom it may concern:

Be it known that I, Ernest L. Shepard, a citizen of the United States, residing at Fairfield, in the county of Somerset, State of Maine, have invented a new, original, and ornamental Design for a Fruit Pack, of which the following is a specification, reference being had to the accompanying drawing, forming part thereof.

Fig. 1 is a top plan view of a fruit pack showing my new design.

Fig. 2 is an end elevation thereof, and

Fig. 3 is a section on the line 3—3 of Fig. 1.

I claim:

The ornamental design for a fruit pack, as shown.

ERNEST L. SHEPARD.
